United States Patent Office.

NICHOLAS S. VEDDER AND FRANCIS RITCHIE, OF TROY, NEW YORK,
ASSIGNORS TO NICHOLAS S. VEDDER.

Design No. 4,374, dated September 27, 1870.

DESIGN FOR STOVE-PLATES.

The Schedule referred to in these Letters Patent and making part of the same.

To all whom it may concern:

Be it known that we, NICHOLAS S. VEDDER and FRANCIS RITCHIE, both of the city of Troy, in the county of Rensselaer and State of New York, have jointly invented and produced certain new and original features in Designs for Stove-Plates, of which the following is a specification, reference being had to the accompanying photograph, in which—

Figure 1 represents a parlor cook-stove, which embodies all the distinguishing features of our new design.

One new feature of our design is the compound ornament A, having its various parts all shaped and arranged together upon and cast with a door or plate of a stove, so as to appear substantially as shown in the aforesaid photograph.

Another feature of our invention is the ornamental design of the skeleton cover B, as shown in the photograph.

Another new part of our design is the shape and ornamentation combined, of and upon the lower top plate C, as shown.

Another new feature of our design is the arrangement, upon the upright lower section D, of the ornaments

e, and moldings f g, as shown in the photograph.

Another new part of our invention is the form and configuration of the raised and inclined perforated ash-pit cover H, as shown.

Another part of our invention is the design for the foot I, as shown in the photograph.

What we claim as our invention and production, and desire to secure by Letters Patent, is—

1. The compound central ornament A, as herein described and shown.
2. The design for the open-work cover B, as shown.
3. The design for the lower top plate C, as shown.
4. The ornamentation of the lower upright section D by the figures and moldings e f g, as shown and described.
5. The form and configuration of the raised and inclined ash-pit cover H, as shown.
6. The design for the foot I, as shown.

NICHOLAS S. VEDDER.
FRANCIS RITCHIE.
